RACK FOR BASEBALL BATS OR THE LIKE

Leslie L. O'Neal, 3132 Via Arcilla,
San Diego, Calif. 92111

Filed Mar. 24, 1975, Ser. No. 561,170

Term of patent 14 years

Int. Cl. D6—04

U.S. Cl. D6—125

Fig. 1

Fig. 2

Fig. 3

Fig. 4

FIG. 1 is a perspective view of a rack for baseball bats or the like, showing my new design.

FIG. 2 is a top plan view thereof.

FIG. 3 is a rear elevational view thereof.

FIG. 4 is an end elevational view as taken from the left hand end of FIG. 3.

I claim:

The ornamental design for a rack for baseball bats or the like, substantially as shown.
